UNITED STATES PATENT OFFICE.

SAMUEL G. MUNN, OF CHICAGO, ILLINOIS, ASSIGNOR TO JAMES MUNN, OF WEST FORK, LOUISIANA.

IMPROVEMENT IN VAPOR-BURNERS.

Specification forming part of Letters Patent No. 122,637, dated January 9, 1872.

To whom it may concern:

Be it known that I, SAMUEL G. MUNN, of Chicago, in the county of Cook and State of Illinois, have invented a new and useful Improvement in Hydrocarbon-Vapor Burners; and I do declare that the following is a true and accurate description thereof, reference being had to the accompanying drawing and to the letters of reference marked thereon and being a part of this specification, in which—

Figure 1 is a perspective view of my improved burner. Fig. 2 is a plan view. Fig. 3 is a cross-section of the same; and Fig. 4 is a perspective of the regulating-cap.

Like letters refer to like parts in each figure.

The nature of this invention relates to an improvement in the construction of a combined hydrocarbon-vapor generator and burner; and it consists in the combination of the deflector, the burner, and certain guides, all as more fully hereinafter described.

In the drawing, A represents the safety-tube filled with the usual packing to prevent burning back. B is the generating-chamber slipped over the top of the tube A. C is a cylindrical burner, rising from the generator, and has a minute orifice, a, in one side near its base. On the same side as this orifice a deflector, D, projects laterally. This deflector curves upward and inward to retain the flame and give it an opportunity to combine with the oxygen of the atmosphere, and thus produce perfect combustion. I am aware that this particular curve or curl of the deflector is not new, and, therefore, disclaim its invention. In addition to this curve I curve the deflector circumferentially throughout its length, with an increased inward curl at the ends, to overcome the difficulty in burners of this class hitherto experienced in the shooting of the vapor past the corners,

and burning with a smoky flame. The fluid carried up by the packing to the generating-chamber is vaporized by the heat communicated to said chamber by the deflector, and issuing from the orifice the vapor strikes the deflector in combustion, is expanded, and spread over its entire surface.

Constructed as above described the burner may be considered as complete; but as it is frequently desirable to reduce the flame and consumption of fluid I place a regulating-cap, E, on the burner, the construction of which is fully shown in Fig. 4 of the accompanying drawing. The cap has an opening, b, through a solid part of its top for the reception of a wire-pin, by which it may be rotated on the burner. In one side is a vertical slot, c, through which the vapor issuing from the orifice in the burner passes. By rotating the cap the flame may be reduced or cut off entirely independently of the stop-cock. If reduced much the jet of flame has a tendency to point off to one side, which tendency may be corrected by placing a guiding, d, between the orifice and the deflector at either side. These guides may be cast on or made of a separate piece of sheet metal bent to the proper form and slipped over the burner. The generating-chamber, burner, and deflector, for convenience, are cast in one piece.

What I claim as my invention, and desire to secure by Letters Patent, is—

The combination of the generating-chamber B, the guides d, the deflector D, the burner C, and the regulating-cap E, provided with the slot c, all constructed, arranged, and operating substantially as described and shown.

SAMUEL G. MUNN.
